TEXTILE ROLL JOINT AND METHOD AND
MEANS FOR FORMING ITJohn L. King, Atlanta, Ga., assignor to Atlanta
Textile Machine Works, a corporation

Application August 17, 1932, Serial No. 629,247

8 Claims. (Cl. 29—86)

This invention relates to a method of and apparatus for the assembling of sectional textile rolls, and to a novel type of assembly unit between the various roll sections which eliminates many 5 of the undesirable features present in rolls now used in the textile art.

Complete rolls of the type to which this invention applies are small in diameter but when assembled into a roll unit they may be from twenty 10 to thirty feet or more in length, and because of mechanical difficulties must necessarily be made up of a number of relatively short sections, and have a number of bearing surfaces or journals to insure a working alignment.

15 In the rolls now being used almost universally the journals are a part of the roll section, and the sections are joined by either a threaded connection or a more or less loosely pressed mortise joint, to be illustrated and described hereinafter. 20 This type of connection causes back-lash, or a reciprocal circumferential play between the sections, which is responsible for uneven feed of the cotton fibers between the fluted portions of the rolls. The journals have a natural tendency to 25 wear out and, since they are an integral part of the roll sections, this means considerable shutdown and replacement expense.

It is an object of this invention to furnish a 30 roll connection which will eliminate back-lash by causing the assembly to approximate a roll of unitary character, the joints being forced together under high pressure.

It is another object to furnish a joint which may be used for restoration of those rolls now in 35 use which have had their journals worn until no longer of practical use.

It is a further object to supply means for forming this connection rapidly and accurately, one 40 form of such means comprising the novel hydraulic press illustrated in the drawings which form a part of this application.

Further objects of the invention will more fully appear as the description proceeds.

Figure 1 is a top view of the press;

45 Figure 2 is a lateral view of the apparatus shown in Figure 1, portions being broken away, and portions shown in section, to better illustrate the operation of the press;

Figure 3 is a vertical sectional view taken on 50 the line 3—3 of Figure 1;

Figure 4 is an enlarged view of the clamping apparatus shown at the right of Figure 1;

Figure 5 is an end view of the apparatus of 55 Figure 4;

Figure 6 is a sectional view taken on line 6—6

of Figure 2, looking in the direction of the arrows;

Figure 7 is a detailed view of one of the front cylinder heads;

Figures 8 and 9 show adjacent ends (separated) 5 of roll sections of the type now in general use.

Figures 10 and 11 show adjacent ends of roll sections prepared for joining according to the method of this invention; and

Figure 12 is a showing of the neck member 10 which coacts with the rolls of Figures 10 and 11, and forms both a connective element and a journal for the completed roll.

is shown detached in Figure 7. The cylinder heads, which are maintained in position by heavy machine screws, are provided with stops 38 which co-operate with stops 37 on the crosshead 27 in limiting the movement of the crosshead toward the cylinders. In the crosshead is a continuation of passageway 33 for the reception of the roll section 34, and a bushing 39 similar to the bushing 35 is provided, and is likewise interchangeable with bushings having larger or smaller openings therethrough. The bushing 39 is secured by a screw member 40 similar to the securing pin 36.

Suitably connected, as by screw threads to the box heads 41 and 42, are sections of tubing 43 and 44, respectively, through which extend the roll sections 34. The tube 43 is also secured as at 43^a in suitable manner to the cylinder block, and remains stationary with it, while the tube 44 is suitably secured as at 44^a to the crosshead 27, and moves with the latter. The box heads 41 and 42 are similar, and are positioned one at the forward end of the machine, and the other at the rear end thereof. One of them is shown in detail in Figures 4 and 5, and a description thereof will suffice for both. It comprises a plate 45 having a sleeve 45^a into which is screwed (or otherwise secured as by splitting and bolting the sleeve sections together as at 53), the outer end 30 of the tube 44. The plate carries extensions 46 on which are pivoted levers 47. Extensions 48 on the levers 47 engage in recesses in clamping jaws 49, which jaws are slidable toward and away from each other, and have semi-circular indentations 50 designed to clamp about and hold securely the depressed portions of roll sections 34. The jaws 49 are slidable in a slot in the plate 51, through which plate extends a further continuation 52 of passageway 33. The plate 51 is secured by screws to the plate 45 as illustrated, and the jaws are removable for interchanging with other jaws of greater or less length, and with greater or less radii of indentations 50 to accommodate the particular size of roll section being assembled.

It will thus be seen that from one box head through the other there is a continuous passageway extending through the machine, through which passageway the roll sections may progress in uninterrupted alignment as they are assembled.

Referring particularly to Figures 1, 2 and 6, the power which drives the piston heads 25 and 31 is derived from hydraulic pressure generated by means of a pump which includes a handle 54 pivoted at 55 to a link 56, which is in turn pivotally connected as at 56^a to an extension 57 on the cover 23. Pivoted to the handle 54 at 58 is a pump rod 59 which operates in a cylinder 60. A valve 61 which opens inwardly from the reservoir 22, and which is positioned in sump 62, allows oil from the reservoir to flow into cylinder 60 when the rod is raised and prevents its return when the rod is driven downward by the handle 54. A second valve 63 opens under the pressure thus generated, and permits oil to flow up a pipe 64 to a horizontal pipe 65 (see Figure 1), on which are two valves 66 and 67, which are utilized in a manner to be hereinafter described in operating the pistons 25 and 31 alternately. Into the reservoir 22 opens a return pipe 86 from both cylinders 21, and the cylinder 32. Pipe 86 connects with a second horizontal pipe 87 controlled by the valves 68 and 69. The rear ends of the pipes 65 and 67 are connected by the cross pipe 70 and

their forward ends are connected by the cross pipe 71. From the pipe 70 extends downwardly a vertical pipe 72, which opens into the cylinder 32, and from pipe 71 a vertical pipe 73 leads to a pressure gauge 74, and to a passageway 75 (see Fig. 6) which divides into ducts 76 opening into the cylinders 21 between the forward ends thereof and the piston 25.

The method of reciprocating the movable parts of the machine, and the method of assembling the roll sections may now be described. Figures 8 and 9 illustrate one of the methods now in common practice over which this invention is an improvement. In such figures, the roll 77 is provided with a journal 78, and a squared shaft 79 made integral with it, the shaft being fitted by sliding fit, and more or less loosely into a squared hole 80 in the end of the adjacent section 81 of the roll. The figures show the sections separated. According to my invention the roll sections illustrated in Figures 10 and 11 are prepared for joining by the cylinder neck 82 which I use, by having cylindrical openings 83 provided in their adjacent ends, which openings are designed to make an extremely tight pressed fit with the neck 82 which is to join the roll sections. The neck 82 is preferably of hardened tool steel, because it is to become one of the journals of the completed roll, and is machined to make a very close fit with the cylinder apertures 83 of the roll sections 34. This forced fit requires a considerable pressure to secure, and the machine will supply this pressure as will more fully appear.

In assembling a roll, two sections 34 are inserted in the machine, one through the opening 52 in the box head 41 from the rear and the other through opening 52 in the box head 42 from the front of the machine. The first of these is pushed through bushing 45^a, tube 43, passageway 33, and bushing 35, and out on the other side of the cylinder casting, until it projects therefrom about three-fourths of an inch, as shown in Figures 2 and 3. It is assumed that the crosshead is in its outermost position with reference to the cylinder block, the pistons 25 being at the forward ends of the cylinders 21 and the piston 31 being at the forward end of the cylinder 32. The other roll section is pushed through bushing 45^a, tube 44, and bushing 39 in the crosshead 27, until it also projects about three-fourths of an inch. The handles 47 of both box heads are then turned until the jaws 49 lock about the depressed portions of the roll sections, and hold them immovable. When the parts are in this position, the distance between the adjacent ends of the roll sections is sufficient to receive the neck 82. The pump is then operated to move the crosshead toward the cylinder, the oil flow being hereinafter described, with the ends of the neck aligned with the openings 83 of the adjacent roll sections, thus forcing the ends of the neck into the roll sections. The movement of the crosshead continues until it is brought to a stop by the engagement of stops 37 on the crosshead with the stops 38 on the cylinder block. In joining the first two sections of a roll, a fine adjustment is always made for the distance to be left between the adjacent ends of the sections after the neck is pressed in, so that every subsequent section is spaced the same to very close limits, and this, without having to measure each section. This is done by adjusting the tube 44 to lengthen or shorten the distance between the box head 45 and the crosshead 27, so that when the space between the ends of the roll sections is

just right (after the neck is pressed in), the stops 37 will be squarely against the stops 38 of the cylinder head. To secure this adjustment, the tube 44 may have a right and left hand thread 5 and may be turned in the one direction or the other, so as to increase or diminish the distance between the front box head and the crosshead. It will be understood that if the split sleeve construction is used in securing the tube to the 10 crosshead and forward box head, the sleeve will be loosened when the adjustment is made and can be retightened to finally fix the crosshead and box head in adjusted position.

To drive the crosshead 27 toward the cylinder 15 casting, valves 66 and 68 are opened, and valves 67 and 69 are closed. The pump is now operated, the oil being forced through the pipe 64, and so to pipe 65. Here its flow is stopped in one direction by the closed valve 67, and hence it passes 20 through valve 66 to pipe 71, and around to the valve 69, which is also closed. Therefore, its only passageway must be down pipe 73 to passageways 75 and 76, and thence to cylinders 21, where it forces back the pistons 25. This movement of 25 the pistons, through their connection by means of the rods 26 with the crosshead, draws the latter toward the cylinder blocks until the stops 37 contact with the stops 38. The gauge 74 will 30 register the pressure during this operation. During this motion the guides 28 have moved back with the crosshead carrying with them the cross bar 29 and piston rod 30, of course moving the piston head 31 towards the rear end of the cylinder 32. This movement will cause the oil which 35 has been dormant in cylinder 32 to move upwardly through pipe 72 to pipe 70. Here it flows in both directions, being stopped by the closed valve 67 in pipe 65, and allowed to pass through pipe 87, valve 68 which is open, and through pipe 86 40 back into the reservoir 22.

At the end of this movement of the crosshead the joint has been completed and it is necessary to prepare for the next. The jaws 49 on the box heads are released, the joined sections are drawn 45 rearwardly through the central passageway until the unconnected end of the section which was in the pipe 44 is now contained in the cylinder block and pipe 43, with such unconnected end extended outwardly about three-fourths of an inch as 50 before. The jaws 49 of the rear box head may now be closed so as to bind the roll section extending out through such box head. The valves 66 and 68 are now closed, and the valves 67 and 69 opened, and pressure is created by the pump. 55 As before, oil is forced in the tank through the pipe 64 into the pipe 65, but now it is stopped by the closed valve 66, and so flows rearwardly through valve 67 and pipe 65, to pipe 70, thence through pipe 72 to cylinder 32 (its flow through 60 pipe 87 being stopped by the closed valve 68). Accumulating in the cylinder 32 it forces the piston 31 forward. This movement causes the cross bar 29, guide rods 28, crosshead 27, and the pipe section associated therewith to move forwardly and away from the cylinder block. The 65 pistons 25 being connected with the crosshead, are also drawn forwardly, thus forcing oil out of the cylinders through the ducts 76 and pipe 73, to pipe 71. The valve 66 being closed, the 70 oil passes through the valve 69 of pipe 87, and by reason of the valve 68 also being closed, thus necessarily passes through pipe 66 back to the reservoir. Thus the parts are again returned to the open position illustrated in the drawings.

75 A new roll section is now inserted in the pipe

44, the jaws of the forward box head are closed about the roll section, a new neck is lined up with the adjacent roll ends, the valves are again reversed, and the pump operated, to again drive the crosshead toward the cylinder block and thus 5 complete the second joint. The adjustment for the distance to be left between the adjacent roll ends after the joint is made, having already been secured in the first operation, no further adjustment is necessary. In this manner, the roll sections 10 are assembled one after the other, the sections being inserted in the forward end of the machine, and the joined sections being pulled through the rear end of the machine, the sections thus passing through the machine from 15 one end to the other during the process of being joined.

It will be observed that the bushings provided in the machine, support the sections in properly aligned position with reference to each other, 20 and that the movable parts of the machine are maintained in proper alignment with the stationary parts thereof by the guide rods. Thus it is only necessary to feed the roll sections into one end of the machine and pull the joined sections 25 out of the other end as the machine is operated, it not being necessary to pay any attention to the alignment of the roll sections, nor to constantly measure the distance left between adjacent ends 30 of joined sections.

I have found that by constructing the joints with cylindrical necks having a pressed fit with the cylindrical openings in the roll section ends, an extremely rigid and tight joint is made, one 35 in which back-lash will not develop, as with other types of joints now in common use, and one in which the necks may form the journals of the rolls, thus eliminating the necessity of providing the rolls with special journals and with squared shafts, such as have been illustrated in Figure 8, 40 and a joint is made which renders the entire roll from one end to the other extremely rigid and straight.

I have given the foregoing detailed description 45 for purposes of clearness of understanding of my invention, but no undue limitations should be deduced therefrom, as the claims should be construed as broadly as permissible, in view of the prior art. Obviously, alterations and changes 50 may be made without departing from the spirit of my invention, or the scope of the claims.

Having thus described my invention, what I claim is:

1. Apparatus for the assembly of sectional rolls comprising a cylindrical block having twin cylinders therein, pistons adapted to reciprocate in the cylinders, a movable frame attached to said pistons, means on the movable frame and on the cylinder block respectively for supporting and locking roll sections in aligned condition, and 55 power means for operating the said pistons.

2. A roll assembling machine comprising a cylinder block having an opening therethrough, a tube carried by the block in alignment with the opening and having means for locking a roll section in position in the cylinder block and tube, a crosshead having an opening therethrough, a tube carried by said crosshead in alignment with said opening and provided with means for locking another roll section in second said tube and 65 70 said crosshead in alignment with the first said roll section, a cylinder in said cylinder block having a piston connected with said crosshead, guide rods connected with the crosshead for movement therewith and slidably supported on 75

- 5 said cylinder block, a second cylinder mounted on said cylinder block and having a piston connected with said guide rods, an oil reservoir on said cylinder block having pipe connections with said cylinders, a pump in the reservoir and connected with the pipe connections, and valves adapted to be alternately operated whereby oil may be directed from said pump alternately into said cylinders.
- 10 10. 3. In a roll assembling machine, stationary means for supporting a roll section, movable means adapted to support a second roll section in alignment with the first, a cylinder having a piston connected with said movable means for forcing it in one direction, a second cylinder having a piston connected with said movable means for forcing it in the opposite direction, an oil reservoir, a pump in said reservoir having pipe connections to said cylinders, and valves in said pipe connections adapted to be alternately opened and closed whereby oil may be pumped first to one cylinder for moving said movable means in one direction and then to said other cylinder for moving said movable means in the opposite direction.
- 15 15. 4. A roll assembling machine comprising a cylinder block provided with a cylinder having a piston therein, a crosshead connected to said piston to move therewith, guide rods slideable in the cylinder block to which the crosshead is connected, a second cylinder having a piston therein connected with said guide rods, means on the cylinder block and on the crosshead for maintaining adjacent roll sections in alignment, an oil supply reservoir, and means for forcing oil from said reservoir alternately to said cylinders.
- 20 20. 5. A roll assembling machine comprising a cylinder block having a passageway for receiving a roll section, means for maintaining the roll section in alignment in said passageway, means
- 25 for locking the roll section in said passageway, a crosshead having a continuation of said passageway, means for maintaining a second roll section in the crosshead in alignment with the first said roll section, means for locking said second roll section in position in the crosshead, and means for reciprocating the crosshead toward and away from the cylinder block.
- 30 6. In a roll assembling machine, a cylinder block having means for maintaining a roll section therein, a crosshead movable toward and away from the cylinder block and having means for maintaining a second roll section in alignment with the first, stops for limiting the movement of the crosshead toward the cylinder block, and power means for moving the crosshead toward and away from the cylinder block.
- 35 7. In a roll assembling machine, a cylinder block having means for maintaining a roll section in fixed position therein, a crosshead having means for maintaining a second roll section in fixed position therein and in alignment with the first said roll section, and for adjusting the position of said second roll section with reference to said crosshead, power means for moving the crosshead toward and away from said cylinder block, and stop means for limiting the movement of the crosshead toward the cylinder block.
- 40 8. In a roll assembling machine, a body portion provided with a passageway for receiving a roll section, means for aligning the roll section in the passageway and for detachably locking it therein, a crosshead having a continuation of said passageway and having means for aligning a second roll section therein and for detachably locking it in position, and means for moving said crosshead toward and away from said body portion.

JOHN L. KING. 40
